BY
Charles H. Lee,
ATTORNEY.

UNITED STATES PATENT OFFICE.

JAMES P. CLARK, OF NEWARK, NEW JERSEY.

WIRED PLATING AND DIPPING RACK.

No. 811,375.

Specification of Letters Patent.

Patented Jan. 30, 1906.

Application filed June 26, 1905. Serial No. 266,926.

To all whom it may concern:

Be it known that I, JAMES P. CLARK, a citizen of the United States, residing at Newark, in the county of Essex and State of New Jersey, have invented certain new and useful Improvements in Wired Plating and Dipping Racks; and I do hereby declare the following to be a full, clear, and exact description of the invention, such as will enable others skilled in the art to which it appertains to make and use the same, reference being had to the accompanying drawings, and to numerals of reference marked thereon, which form a part of this specification.

15 The objects of this invention are to provide a dipping rack or holder which will be more durable and less liable to reduce the electrolytic fluid because of undue deposition of metal on the rack and to secure other advantages and results, some of which may be hereinafter referred to in connection with the description of the working parts.

20 The invention consists in the improved dipping-rack for electroplating articles and in the arrangements and combinations of parts of the same, all substantially as will be hereinafter set forth, and finally embraced in the clauses of the claim.

25 Referring to the accompanying drawings, in which like numerals of reference indicate corresponding parts in each of the several figures, Figure 1 is a front elevation of the improved rack. Fig. 2 is a side view of the same, partly in vertical section. Fig. 3 is a 30 sectional view taken at line x. Fig. 4 is a detail view of a portion of a certain center piece or bar; and Fig. 5 is a section thereof, taken at line y.

35 In said drawings, 6 indicates a center piece or bar to which a series of transverse bars 7 are rigidly secured, the said bars being preferably of wood or other non-conductive material and of sufficient strength to sustain a number of articles to be plated. To each of 40 the said transverse bars are attached a series of metallic hooks 8, from which the articles to be plated are suspended, said hooks being preferably of wire, and being electrically conductive and each of a series connected to a common transverse wire 9, extending lengthwise of the said transverse pieces or bars 7. Said wires 9 are in turn each in electric connection with a vertical wire 10, which is preferably hooked at its upper end, as at 45 11, and serves as a suspensory supporting connection for the rack. The wooden up-

right or center bar 6 is preferably grooved longitudinally at about the longitudinal center of its front face as at 12, in Figs. 3 and 5. The said groove serves as a receptacle for the 50 conducting and supporting wire 10.

To prevent the wires 9 and 10 from being coated with an electrodeposit of metal from the electrolytic bath, the said wires are covered and protected from such fluid by plates 65 13, of wood, which cover the grooves, and in like manner the wires 9 in grooves 71, Fig. 3, of the transverse pieces, preferably at the sides opposite that from which the hooks project, are protected by horizontal covering 70 pieces 14, attached to the horizontal bars 7.

In the preferred construction the hooks 8 are doubly hooked or hooked at opposite ends, at their upper ends being bent to extend around the wires 9, lying in the longitudinal grooves of the strip 7, and thus said hooks are not only brought into close contact with said wires 9, but the said hooks are held in place with greater security and firmness, as will be obvious. From said conducting 80 and supporting wires 9 the hooks project through perforations in the bar 7 and thence downward to receive articles to be plated. I prefer to arrange the hooks of one series so that they project oppositely from the hooks 85 of the series next above and below, as indicated in Fig. 2. By this arrangement I am enabled to suspend a larger number of articles from the rack without interference, as will be obvious, which conduces to economy 90 and quick results. When said hooks are thus oppositely disposed, I prefer to double the suspensory-wire 10, as shown in Fig. 2, where the said wire extends longitudinally downward at one side of the central bar and then 95 passes through a hole in said bar and thence extends upward at the opposite side of the said bar, the said extensions being all protected by applied pieces of non-conductive matter. 100

Having thus described the invention, what I claim as new is—

1. The improved plating-rack, comprising a center bar, a series of transverse bars secured to said center bar and a series of hooks 105 supported by one of said transverse bars, and protected conducting-wires in electrical connection with said hooks and with a suspensory conducting-wire.

2. The combination with the longitudinally-grooved center bar and longitudinally-grooved horizontal bars attached thereto of

conducting-wires arranged in the grooves of said bars and hooked wires in connection with the wires of the horizontal bars, substantially as set forth.

3. The improved rack, comprising a series of horizontal bars having longitudinal conducting-wires protected by insulation and thus prevented from coming into contact with the electrolytic fluid, of wire supports for the article to be plated, hooked onto said conducting-wires and in electrical contact therewith.

4. The improved plating-rack having a horizontal bar with a protected conducting-wire arranged longitudinally thereon, and a

series of wire supports for the article to be plated, extending through said bar and at the side of said bar opposite the supporting extension of said wire hooked onto said conducting-wire the said wire-supports being in ²⁰ electrical contact with said conducting-wire, substantially as set forth.

In testimony that I claim the foregoing I have hereunto set my hand this 16th day of June, 1905.

JAMES P. CLARK.
